Portland, Maine, a corporation of Maine

Application September 10, 1930, Serial No.
480,898, and in Great Britain September 19,
1929

29 Claims. (Cl. 149—17)

This invention relates to machines for treating hides, skins, leather, and other similar pieces of work and is illustrated as embodied in a staking machine for stretching and softening pieces of leather. It is to be understood, however, that the invention and various important features thereof may have other applications and uses.

In United States Letters Patent No. 1,101,763, granted June 30, 1914, upon application of F. F. 10 Slocomb, there is disclosed a staking machine provided with a pair of staking tools arranged to co-operate with a member having a recess, the arrangement being such that one of the staking tools forces a portion of the piece of work undergoing treatment into the recess, so that as the said member and the tools reciprocate together, during work-treating operations, portions of the work are forced into the recess and around the edge of the tool projecting into the recess. This 15 machine was not entirely satisfactory due to the fact that the last portion of the work to pass by the edge of the tool in each operative stroke thereof was not treated as effectively as the rest of the work. It will be understood that, in the operation 20 of the machine, the tool not in the recess serves to hold the work frictionally and thus co-operates with the tool which presses the work into the recess. When, however, at the last part of the stroke this co-operating tool drops off of the work, 25 the latter is at once released so that it passes around the edge of the tool in the recess with much less tension upon it and hence is not so effectively treated. Moreover, in the patented machine, wherein the tools yield individually with respect to 30 the work, no provision was made for varying self-adjustingly the total pressure of the tools on the work to ensure proper accommodation of the tools to variations in the thickness of the portions of the work passing under the tools at any given instant.

40 Objects of this invention are to improve the quality of the results obtained in staking operations in general, and, more specifically, to improve the operation of machines of the type of the patented machine mentioned in the foregoing 45 paragraph.

To this end and in accordance with an important feature of the invention, means is provided for supporting portions of the work against the thrust of work treating tools so constructed and 50 arranged as to insure the desired treatment of all portions of the work, including the marginal portions thereof, by increasing the tool effectiveness on said marginal portions. Conveniently, the tools are so arranged that as one tool drops off 55 the edge of the work another tool presses with

increased pressure upon the work, thus compensating for the lost tension normally effected by the first-mentioned tool when the tools are in engagement with the work. In the illustrated construction, there is provided a member having 60 work-supporting surfaces against which portions of the work are pressed by a pair of work-treating tools mounted for independent movement relatively to each other, so that as one tool drops off the work the other tool will receive all of the 65 pressure theretofore borne by both tools.

In order that variations in the thickness of the work in the path of the tools may be accommodated to secure the best results, means is 70 preferably provided for applying a predetermined pressure to the tools comprising spring means permitting the tools to yield together away from a work-supporting member, means being also provided for permitting yielding of each tool, individually.

These and other features of the invention and novel combinations of parts will now be described in detail and then pointed out more specifically in the appended claims.

In the drawing,

Fig. 1 is a view in side elevation of the operative parts of a staking machine illustrating one embodiment of the invention;

Fig. 2 is an enlarged view of the work-treating parts shown in Fig. 1;

Fig. 3 is a view of the work-treating parts looking from the left in Fig. 2; and

Fig. 4 is a plan view, on a smaller scale, of the work supporting parts taken on line IV—IV of Fig. 1.

In the illustrative embodiment of the invention, designed for use in staking operations upon hides and skins, a tool head 1 is suspended from a lever 2 pivotally mounted at 3 on a carriage 4 which is slidable in machine frame 5 above an inclined work table or bed 6 rigidly mounted by brackets 8a (Fig. 3) on a movable support comprising spaced members 6a in which a slide 7 travels, said slide 7 being retained on the member 6a by strips 7a which overlap reduced 100 flange portions of the slide 7 as shown in Fig. 3. The carriage 4 and slide 7 are connected by a link 8 and reciprocated by a crank (not shown) through a connecting rod 9, link 8 being connected to slide 7 by curved arms 9a rigid with the slide 7. As shown, rod 9 is connected pivotally to carriage 4 by a gudgeon pin 10. On an arm of the rod 9 extending upwardly from pin 10 is a cam 11 oscillated during the operative strokes of the working tool and slide, so 110

that the lever 2 is caused to push a tool 12 on tool head 1 into a gap or recess 13 in the slide 7. The gap or recess is formed by two spaced transverse jaws or bars 14 (Fig. 2) secured to the slide 7. Secured to each end of the slide 7, which is of limited length, is a belt 14^a which passes around rollers 14^b and 14^c journaled in the movable support comprising spaced members 6^a. Since the slide 7 is reciprocated in the space between the members 6^a, it is performance limited in its length dimension, and it is to support the work and prevent it from sagging or dropping into the space between the members 6^a that the belt 14^a is provided.

15 In order that the slide 7 with its recess 13 may be moved upwardly to operative position wherein the tool 12 may push a portion of the work down into the recess 13, the movable support comprising the spaced members 6^a is mounted

20 for movement in a vertical direction between guide members 14^d (Fig. 3) and is operated by a treadle (not shown), all as fully described in said Letters Patent No. 1,101,763.

A block 15 is provided in the gap or recess 25 13 upon which the work α is pressed by the working tool 12. The block 15 conveniently consists of a piece of hard wood such, for example, as lignum vitae, and has a groove 16 in one face. The block is inserted between the said jaws or bars 14 with the groove uppermost and rests upon the slide 7. While any suitable means such as screws may be adopted for securing the block in position, it is preferred to make the block a push fit between the bars or jaws. This method 30 has the advantage of being both simple and effective and, moreover, a block can be readily inserted and removed. If desired, blocks respectively formed with different grooves may be provided for use in conjunction with different 35 tools, said blocks being interchangeable.

In connecting the tool head 1 with the cam actuated lever 2, according to one construction, said lever 2 has a plurality of studs 17 fixed vertically therein and the tool head 1 is attached 45 to one end of a rod or link 18 which, at the other end, is pivotally connected to a block 19 slidably on the studs 17 in the lever 2. Strong compression springs 20 are provided on the studs above the block 19 and are held in position thereon by nuts 21 and washers 22. By reason of this arrangement the tool head 1 can yield, if and when (as the tool presses the work on to the block in the slide) variations in the thickness of the work are encountered. Suitable provision 50 is made through the adjusting nuts 21 for regulating the pressure of the springs 20 so that normally the work is gripped between the working tool 12 and the block 15 sufficiently to enable the required results to be achieved.

60 As is well known, for staking and softening operations a tool having a beveled end is usually employed. By employing a tool similar to tool 12 but having a rounded end, in conjunction with a back tool 23 controlled by an adjustable rubber buffer, indicated generally at 24, the machine can be adapted to perform setting operations on pieces of leather very satisfactorily.

In the illustrated machine, during the main 70 part of the working stroke the tools 12 and 23 press on the work to an extent determined by the regulation of the spring means 20 and the rubber buffer 24 associated with the back tool. The pressure on either tool can never exceed the pressure exerted by the spring means 20. When, 75 toward the end of each working stroke, the back

tool 23 leaves the work, the pressure on this tool is relieved and the whole of the pressure exerted by the spring means 20, which previously was divided between the two tools, is concentrated on the front tool 12, i. e., the pressure on the front tool 12 automatically increases after the back tool 23 has left the work. As the tensioning effect of the back tool 23 on the work is lost, the concentration of the whole of the pressure on the front tool 12 is beneficial for the reason that the remainder of the work, which is about 1 inch or 1½ inches in width, receives the additional pressure and is especially stretched or softened.

80 For mounting the staking tool 12 on the tool head 1 there is provided a member 30 pivoted at 32 on the head 1, the upper end of the member 30 having a screw threaded opening for reception of a pin 34. As shown most clearly in Fig. 2 of the drawings, the pin 34 extends loosely through an opening in a bracket 36 rigid with the tool head 1 and has mounted thereon a rubber cushion 38. For holding the rubber cushion 38 on the pin 34 there is provided a locking nut and an abutment member both indicated at 40.

85 Upon rotating the locking nut and abutment member 40 in the proper direction, tension on the rubber cushion 38 may be varied as desired. It is clear from the above description that the staking tool 12 may yield in a direction away from the arrow in Fig. 2 through compression of the rubber cushion 38. Similarly the tool 23 may yield upwardly away from the block 14, to accommodate thicker portions of the work, through compression of the rubber cushion 24. As heretofore stated both tools 12 and 23 may 90 yield in a direction away from the work, to accommodate thicker portions thereof, through compression of springs 20 mounted upon the studs 17 carried by the lever 2.

95 For clamping a piece of work upon the table 6 115 there is provided, in the illustrated construction, a clamping member 50 having a work contacting pad 52 at its lower end and an intermediate perforated portion 54 for the reception of a pivot pin 56 by which the member 50 is pivoted to the 120 machine frame 5. Pivotally attached to the upper end of the clamping member 50 at 58 is a link 60 the other end of which is in turn pivotally attached to the upper end of a lever 62 the lower end of which has pivotally attached thereto a connecting rod 64 arranged to be operated by means (not shown) to cause the clamping member 50 alternately to clamp and release a piece of work 125 placed in position upon the table or bed 6.

130 In the operation of the machine, a piece of leather to be staked is introduced by the operator and placed upon the table or bed 6, a portion of the piece of leather being arranged to project over the front end of the table 6 between it and the clamping pad 52. When the machine is ready for staking operations, it is being run continuously through power means (not shown) provided for the purpose. During this continuous operation, the slide 7 and the carriage 4 (carrying the tools 12 and 13) are reciprocated back and forth at a 140 relatively rapid rate. But it is only when the operator elevates the vertically movable support for the slide 7 by depressing the treadle (not shown) that operations on the work take place. The skilled operator will depress the treadle at 145 the instant the slide 7 and the carriage 4 are at the limit of their travel toward the left in Fig. 1. Immediately thereafter the staking tools 12 and 23 press portions of the work against the block 15 and the block 14, respectively. After 150

engagement of the staking tools with the work has taken place in the manner described above, the tools and the slide 7 are, together with the blocks 14 and 15, moved rearwardly in a direction away from the clamping pad 52 in Fig. 1 whereby a strip portion of the work is caused to pass between the tools and the co-operating surface on the blocks 14, 15, the result being a staking operation upon the strip portion of the work extending up to the very edge of the work in the path of the tools. As soon as the tools have reached the rear end of their stroke they rise to release the work, the clamp 50 being also moved to releasing position at the same time, thus permitting the operator to shift the work to a new position preliminarily to a repetition of the operative stroke of the tools and slide. These operations are repeated on a given piece of work each time the operator depresses the treadle until all portions have been operated upon.

Having thus described my invention, what I claim as new and desire to secure by Letters Patent of the United States is:

1. In a machine for operating upon hides, skins, leather and other similar pieces of work, a plurality of tools mounted for relative movement with respect to each other, a member for supporting portions of a piece of work against the thrust of said tools, means to cause relative movement between the piece of work and the tools in the direction of a linear dimension of the work while the tools are pressing the work against said member, and means to cause one of the tools to increase its pressure on the work at a predetermined distance from an edge portion thereof.

2. In a machine for operating upon hides, skins, leather and other similar pieces of work, a pair of tools mounted for relative movement with respect to each other, a member for supporting portions of a piece of work against the thrust of said tools, means to cause relative movement between the piece of work and the tools in the direction of a linear dimension of the work and of the spacing of the tools with respect to each other, whereby the tools operate upon successive portions of the piece of work, one tool in advance of the other, while both tools press the work against said member, and means to cause one tool to increase its pressure on marginal portions of the work as they pass from the other tool in advanced position.

3. In a machine for operating upon hides, skins, leather and other similar pieces of work, a plurality of tools mounted for relative movement with respect to each other, means arranged to support portions of the work against the thrust of the tools, means to cause relative movement between the work and said tools, the tools being arranged to press portions of the work against said supporting means, and means to cause one of the tools to increase its pressure on the work as another of the tools drops off an edge portion of the work.

4. In a machine for operating upon hides, skins, leather and other similar pieces of work, a plurality of tools mounted for relative movement with respect to each other, means arranged to support portions of the work against the thrust of the tools, means to cause relative movement between the work and said tools, the tools being arranged to press portions of the work against said supporting means, and means to cause one of the tools to increase its pressure on the work in its line of thrust in timed relation to release of the work by another tool.

5. In a machine for operating upon hides, skins, leather and other similar pieces of work, a plurality of tools for operating on the work, means arranged to support portions of the work against the thrust of the tools, means to cause relative movement between the work and said tools, the tools being arranged to press portions of the work against said supporting means in directions normal to the supporting surface of the supporting means, means to mount the tools for movement independently of each other, and means to cause one of the tools to increase its pressure on the work as another of the tools drops off an edge portion of the work.

6. In a machine for operating upon hides, skins, leather and other similar pieces of work, a plurality of tools for operating on the work, one tool having a bladed edge for treating the work and another tool having a work contacting edge for putting pressure on the work, means to cause relative movement between the work and said tools, means arranged to support the work comprising a member having a grooved surface to support the work in the line of thrust of the bladed tool, and means to mount the blade-edged tool for yielding contact with the portion of the work on said grooved surface.

7. In a machine for operating upon hides, skins, leather and other similar pieces of work, a plurality of tools comprising a bladed tool movable relatively to another tool, means arranged to support a portion of a piece of work against the thrust of the tools, means to cause relative movement between the tools and the work in the direction of a linear dimension of the latter while a portion thereof is being pressed by the tools against said work supporting means, and means to move the tools so that they press portions of the work upon said work supporting means in a direction substantially normal to the work supporting surface thereof, said work supporting means comprising a member arranged to back the work in the line of thrust of the bladed tool, and means to cause increase of pressure of the bladed tool on the work when said other tool drops off the end of the work.

8. In a machine for operating upon hides, skins, leather and other similar pieces of work, a plurality of tools, a member for supporting a portion of a piece of work against the thrust of the tools, means to cause relative movement between the piece of work and the tools in the direction of a linear dimension of the work whereby the work moves relatively to the tools while portions thereof are being pressed by the tools against said member, and means to move the tools so that they press portions of the work upon said member in a direction substantially normal to the work supporting surface of said member, said last-mentioned means comprising means to cause one of the tools to operate at an increased pressure on marginal portions of the work.

9. In a machine for operating upon hides, skins, leather and other similar pieces of work, a plurality of work treating tools, a plurality of members for supporting portions of a piece of work against the thrust of said tools, means to cause relative movement between the piece of work and the tools in the direction of a linear dimension of the work while the tools are pressing the work against said members, means to press the tools toward said members, said tools being mounted for independent movement with respect to each other, and means rendered op-

- erative by one tool dropping off the rear end of the work to cause another tool to receive an increased pressure corresponding to that released by the tool which has just become inoperative.
- 5 10. In a machine for operating upon hides, skins, leather and other similar pieces of work, a plurality of tools for operating on a piece of work, means arranged to support portions of the work against the thrust of the tools, means to cause relative movement between the work and said tools, the tools being arranged to press portions of the work against said supporting means in directions normal to the supporting surface of the supporting means, means to mount the tools independently of each other, and a single means arranged to press both tools against the work whereby as one tool drops off the rear end of the work another tool receives the pressure released by the tool which has just become inoperative.
- 15 20. 11. In a machine for operating upon hides, skins, leather and other similar pieces of work, a plurality of tools, a member arranged to support a portion of a piece of work against the thrust of the tools, means to cause relative movement between the piece of work and the tools in the direction of a linear dimension of the work while the tools are pressing the work against said member, means to move the tools so that they press portions of the work upon said member in a direction substantially normal to the work supporting surface of said member, and a single means arranged to press the tools against the work, said tools being mounted for relative movement while under pressure so that as one tool drops off of the work another tool operates with an increased pressure corresponding to that released by the tool which has just become inoperative.
- 25 30. 40. 12. In a machine for operating upon hides, skins, leather and other similar pieces of work, a pair of work treating tools, a slide arranged to support a portion of the work, said slide having a block to back a portion of the work against the thrust of one of the tools, a second block to support another portion of the work against the thrust of another work treating tool, means to cause the slide and the tools to move while the work is held stationary whereby the work is treated by the tools, and means to cause one of the tools to press with increased pressure on its block when the other tool drops off of the end of the work.
- 35 45. 55. 60. 65. 70. 75. 13. In a machine for operating upon hides, skins, leather and other similar pieces of work, a pair of work treating tools, a slide arranged to support a portion of the work, said slide having a recess, a block located in the recess and having a work supporting surface below the surface of the slide, one of the tools being arranged to co-operate with the work supporting surface of the block while the other tool holds another portion of the work against the work supporting surface of the slide, means to move the slide and the tools relatively to the work, and means to cause one of the tools to engage the work with increased pressure upon a marginal portion thereof.
- 80 85. 90. 95. 100. 105. 110. 115. 120. 125. 130. 135. 140. 145. 150. 14. In a machine for operating upon hides, skins, leather and other similar pieces of work, a pair of work treating tools, a slide arranged to support a portion of the work, said slide having a block to back a portion of the work against the thrust of one of the tools, a second block arranged to support another portion of the work against the thrust of another work treating tool, means to press the tools towards said blocks, means to reciprocate the slide and the tools together relatively to the work to cause a portion of the work to be passed between the tools and the block, said tools being mounted independently of each other, and means to cause one tool to receive all of the pressure, formerly received by both of the tools, after the other tool leaves the work.
15. In a machine for operating upon hides, skins, leather and other similar pieces of work, a pair of work treating tools, a slide arranged to support a portion of the work, said slide having a recess, a block located in the recess and having a work supporting surface below the surface of the slide, one of the tools being arranged to co-operate with the work supporting surface of the block while the other tool holds another portion of the work against the work supporting surface of the slide, means to move the slide and the tools relatively to the work, means to mount the tools for movement independent of each other, and means to cause the tool and block to engage the work with increased pressure at the instant the other tool and the slide cease to engage the work.
16. In a machine for operating upon hides, skins, leather and other similar pieces of work, a plurality of work contacting tools, a slide having surfaces to support portions of a piece of work against the thrust of the said tools, means common to both tools yieldingly to press the tools against portions of the work where it is backed by the work supporting surfaces of the slide, means to cause movement of the tools and the slide relatively to the work whereby the tools are caused to operate on the work as the latter passes between the tools and the work supporting surfaces, and means to mount the tools for movement relatively to each other so that as one tool drops off the edge of the work before another, said other tool receives the yielding pressure formerly received by the tool which has just become inoperative.
17. In a machine for operating upon hides, skins, leather and other similar pieces of work, a plurality of work contacting tools, a slide having surfaces arranged to support portions of a piece of work against the thrust of the said tools, means yieldingly to back each tool so that it may yield to accommodate portions of the work of different thicknesses upon the work supporting surfaces of the slide, means to cause movement of the tools and the slide relatively to the work whereby the tools are caused to operate on successive portions of the work during relative movement of the latter with respect to the tools and the work supporting surfaces, a tool head arranged to support the tools, and means arranged to press the tool head yieldingly toward the slide so that the total pressure on the tool head may be supported by one or both tools whereby as one tool drops off the work another tool receives the yielding pressure formerly received by the tool which has just become inoperative.
18. In a machine for operating upon hides, skins, leather and other similar pieces of work, a surface against which a portion of a piece of work may be clamped, a pair of tools to contact with a piece of work, a slide having surfaces arranged to support spaced portions of a piece of work, the tools being mounted for movement relatively to each other and to the slide.

- to press the said portions of the work against the work supporting surfaces in directions normal to those surfaces, and means to cause movement of the tools and slide in a direction away from said clamping surface. 5
19. In a machine for operating upon hides, skins, leather and other similar pieces of work, a pair of tools to operate on a piece of work, a work supporting surface, a tool head to support the tools, means to press the tool head and tools yieldingly toward the work supporting surface, and means associated with the tools and tool head yieldingly to back the tools to permit them to accommodate themselves to variations in thickness of the work passing over said work supporting surface during the operation of the tools. 10
20. In a machine for operating upon hides, skins, leather and other similar pieces of work, a pair of staking tools to operate on a piece of work, a slide having two surfaces at different levels with respect to each other to support spaced portions of a piece of work, the tools being mounted for movement relatively to each other and to the slide to press the work against the work supporting surfaces in directions normal to those surfaces, and means to cause movement of the tools and the slide in a direction substantially parallel to a plane coinciding with one of the work supporting surfaces of the slide. 15
21. In a machine for operating upon hides, skins, leather and other similar pieces of work, a pair of staking tools to operate on a piece of work, a slide having a recess and a work supporting block in the recess, said slide and block each having a work supporting surface, a tool head to support the tools, means to press the tool head and tools yieldingly toward the work supporting surfaces of the slide and block, means to move the slide and tools relatively to the work, and means associated with the tools and tool head yieldingly to back the tools to permit them to accommodate themselves to variations in thickness of the work upon said work supporting surfaces during the operation of the tools. 20
22. In a machine for operating upon hides, skins, leather and other similar pieces of work, a pair of tools co-operating with each other for stretching operations upon a piece of work, a slide arranged to support portions of the piece of work against the thrust of the two tools, a tool head, means to press the tool head and the tools yieldingly toward the work, means yieldingly to hold the tools in predetermined positions relatively to each other on the tool head, and means to cause movement of the tools and slide in a plane substantially parallel to the work supporting surface of the slide, said slide having a grooved block located below the surface of the slide for receiving a portion of the piece of work as it is forced thereagainst by one of the tools, the construction and arrangement being such that the tool which co-operates with the grooved block receives increased pressure at the instant that the other tool drops off the rear edge of the work during the described relative movement of the work and tools. 25
23. In a machine for operating upon hides, skins, leather and other similar pieces of work, a staking tool and a tool co-operating therewith for stretching operations upon a piece of work, a slide arranged to support portions of the piece of work against the thrust of the two tools, a tool head, means yieldingly to hold the tools in predetermined positions relatively to each other on the tool head, spring means to force the tool head and tools yieldingly toward the slide, and means to cause movement of the tools and slide in a plane substantially parallel to the work supporting surface of the slide, said slide having a grooved block located below the surface of the slide for receiving a portion of the piece of work as it is forced therein by one of the tools, the construction and arrangement being such that the tool which co-operates with the grooved block receives increased pressure at the instant that the other tool drops off the rear edge of the work during the described relative movement of the work and tools. 30
24. In a machine for operating upon hides, skins, leather and other similar pieces of work, a staking tool, a tool for co-operation with the first-mentioned tool in stretching operations on a piece of work, a slide having upwardly facing surfaces arranged to support portions of a piece of work against the thrust of said tools, means to clamp a piece of work and hold it against movement in one direction, means to move the tools into yielding contact with portions of the work located on said work supporting surfaces, and means to move the tools and the slide after they have contacted with the work in a direction away from the clamping means to operate along a strip of the work extending in a direction away from the clamping means. 35
25. In a machine for operating upon hides, skins, leather and other similar pieces of work, a staking tool, a tool for co-operation with the first-mentioned tool in stretching operations on a piece of work, means having upwardly facing surfaces arranged to support portions of a piece of work against the thrust of said tools, a tool head, means to mount the tools on the tool head to yield individually, and means to mount the tools and tool head to yield together away from the work supporting means. 40
26. In a machine for operating upon hides, skins, leather and other similar pieces of work, a staking tool, a tool for co-operation with the first-mentioned tool in stretching operations on a piece of work, a slide having upwardly facing surfaces arranged to support portions of a piece of work against the thrust of said tools, means to clamp a piece of work and hold it against movement in one direction, a tool head, means to mount the tools on the tool head for yielding movement relatively to each other, means to move the tools into yielding contact with portions of the work located above said work supporting surfaces, and means to move the tools and the slide after they have contacted with the work in a direction away from the clamping means to operate along a strip of the work extending in a direction away from the clamping means. 45
27. In a machine for operating upon hides, skins, leather and other similar pieces of work, a staking tool, a tool for co-operation with the staking tool during a stretching operation upon a piece of work, a work support having a grooved block for co-operation with the staking tool and also a work supporting surface for co-operation with the second-mentioned tool, means to cause relative movement between the tools and the work to stretch the latter, a tool head to support the tools, means comprising a lever constructed and arranged to move the tool head and tools in a direction toward the grooved block and slide, spring means interposed between the lever and the tool head whereby both tools are pressed 50

yieldingly upon the work, and means to mount the tools for independent movement upon the tool head, whereby when one tool releases the work the other tool takes the full pressure of the 5 spring means interposed between the lever and the tool head.

28. In a machine for operating upon hides, skins, leather and other similar pieces of work, a staking tool, a tool for co-operation with the 10 staking tool during a stretching operation upon a piece of work, a work support having a grooved block for co-operation with the staking tool and also a work supporting surface for co-operation with the second-mentioned tool, means for causing 15 relative movement between the work and the tools and work support in a direction to stretch the work, a tool head to support the tools, yielding means associated with the tools and with the tool head yieldingly to hold the tools in predetermined 20 relation to each other as they engage the work, means comprising a lever constructed and arranged to move the tool head and tools in a direction toward the grooved block and slide, spring means interposed between the lever and the tool

25

head whereby both tools are pressed upon the work with a predetermined total of pressure, and means to mount the tools for independent movement upon the tool head, whereby when one tool releases the work the other tool takes the total 80 pressure of the spring means interposed between the lever and the tool head.

29. In a machine for operating upon hides, skins, leather and other similar pieces of work, a plurality of tools for operating on the work, 85 means arranged to support portions of the work against the thrust of the tools, means to cause relative movement between the tools and the work in the direction of a linear dimension of the latter, the tools being yieldingly mounted to press portions of the work with a yielding pressure against said supporting means, and means to increase the work treating effect of one of the tools as another of the tools drops off the work, 90 whereby marginal portions of the work are effectively treated despite the reduction in the number of tools operating on said marginal portions.
